UNITED STATES PATENT OFFICE.

ANTOINE VERICEL, OF BALDWIN, NEW YORK, ASSIGNOR TO DOEHLER PRODUCTS CORP., A CORPORATION OF NEW YORK.

METAL FURNITURE.

Application filed November 2, 1926. Serial No. 145,726.

My invention has particular reference to articles of furniture which are intended to be sat upon, such as chairs or the like, although in certain respects my invention is applicable 5 to other types of furniture. My invention will perhaps find its chief utility in metal seats, and, since my invention is well exemplified by an embodiment in a metal chair, I shall use that embodiment as the illustration 10 with which to explain my invention.

Furniture by its very nature is as a rule of considerable bulk and occupies an undue amount of space for shipment. The trend has therefore been toward collapsible or knock-down furniture, as it is known, that is, furniture in separable sections which can be assembled in situ. In my co-pending application Serial Number 124,946, filed July 26, 1926, I have disclosed an article of furniture 15 of that character. That particularly is the type of furniture which has drawers, such as a bureau, one advantage of which is the fact that it is wholly self-contained and is very easily assembled and set up and dispenses altogether with the use of any screws or bolts without any sacrifice in strength or rigidity.

To an increasing extent metal is replacing wood as the material from which furniture is made, and the problems which arise in devising a collapsible or knock-down chair are best solved in metal. Appearance and weight limitations restrict the size of the parts, and nevertheless the character of use is such that a maximum of strength and firmness is required. This is further complicated by the desirability of so sectioning the chair that each section is flat, in order to reduce to a minimum the space occupied by the knocked-down chair.

One of the merits of my invention is the fact that the requisite strength is provided at the joints between the seat and the legs, where the chief strain comes upon a chair or like article. Another feature which characterizes 45 my invention is the fact that when fabricated of metal the chair or other article can be made virtually as light as when made of wood, and this for the reason that the sections are such that they mutually reinforce each other and so distribute the strains as to permit the parts to be made of relatively small cross-section.

Another feature characterizing my invention is the fact that the sectioning is such that

the last section to be inserted is the key-section, in that it serves as the lock for all the other sections. This key-section naturally will be the seat since that is the part which primarily receives the weight. 55

In a satisfactory embodiment of my invention, two of the flat sections are similar, each being composed of a side seat-supporting or frame member with a leg at one end integral therewith, another section is composed of the other two legs joined at the top by a cross-piece which interlocks at its ends with the free ends of the respective side members, and the flat seat forms the key-section, being fashioned to interlock with the opposite ends of the side members and with the cross-piece. 60 65 If the seat is a chair and has a back, the back may be integral with the separate leg section if that be the back legs, but I have found that the article is stronger and more rigid if the top and inside of the back comprise one section, and the side pieces be integral upright extensions of the seat side pieces with provision for suitable interlocking with the other back section. The advantage of this is 70 75 the fact that an occupant of the chair usually leans against the back at the same time that his weight is on the seat, and therefore there is less tendency to racking or twisting the frame of the chair as he moves or shifts his weight therein, than would be the case if the frame members of the seat and back were jointed. 80 85

Other features and advantages of my invention will appear from the following description. I shall now describe the illustrated embodiment of my invention and shall thereafter point out my invention in claims. 90

Fig. 1 is a perspective view of the assembled metal parts of an embodiment of my invention. 95

Fig. 2 is a perspective showing the several sections separated but in their respective relative positions for assembly.

Fig. 3 is a perspective view of the complete chair. 100

Fig. 4 shows the sections disassembled and arranged for packing.

Fig. 5 is a fragmentary section of the chair from front to rear.

Fig. 6 is a sectional detail through one side 105 of the seat as indicated by line 6—6 of Fig. 5.

The illustrated chair is made of metal, the several sections being of such shape that

they may be economically die-cast. It has five sections in the form shown, there being a pair of side members 1 and 2, which are similar, but reversed in right relation; a back 5 leg section 3, a back rest 4 and a seat 5. The side members 1 and 2 have a doubled bend and constitute side seat-pieces 1^a and 2^a, the front legs 1^b and 2^b integral with the front ends of the respective side-pieces, and upright side 10 back-pieces 1^c and 2^c integral with the rear ends of the respective side-pieces. The side back-members 1 and 2 are provided at their upper ends with mortises 6 and 7 and also with side mortises 8 and 9 in their respective 15 inner sides, as shown. The back rest member 4 is provided with tenons 11 and 12 adapted to cooperate with the top mortises 6 and 7 and additional tenons 13 and 14 to cooperate with the side mortises 8 and 9.

20 The back leg section 3 is composed of the two rear legs 3^a and 3^b connected at their top ends by a cross piece 3^c. This cross piece is channeled longitudinally of its front face to enable it to interlock suitably with the seat 25 portion 5, as will be hereinafter explained. The cross piece at its ends in line with the respective legs is provided with mortises 15 and 16. The side-sections 1 and 2 are equipped with depending tenons 17 and 18, 30 respectively, in line with the side back-sections 1^c and 2^c, which tenons are adapted to cooperate with the mortises 15 and 16 in the rear leg section 3. The channeled portion of the cross-section 3^c extends only for the distance inside of the side-sections when the parts are assembled, a shoulder being thus provided near each end of the cross-piece to bear against the inner corners of the side-sections and assist in rendering these joints 35 more rigid when the parts are assembled.

40 The side seat-pieces 1^a and 2^a are also provided with mortised bosses 19 and 20 on the front ends of their respective inner faces. The seat-section 5 is provided with an interlocking ledge 21 at its rear edge and also with tenons 22 and 23 on its under side at its opposite front corners in position to cooperate with the mortises in the bosses 19 and 20. In addition, lugs 24 and 25 are provided on 45 the respective inner faces of the side seat-pieces 1^a and 2^a near their rear ends. These lugs have flattened upper faces and are of the correct height to provide a bearing for the seat member 5. The tenons 22 and 23 are equipped with spring washer clips 22^a and 23^a, respectively, at their lower ends. These 55 spring washers are adapted to enter through the mortises in the bosses 19 and 20 and to expand after clearing the lower edges thereof so as to hold the tenons 22 and 23 in place in the mortises. The ledge 21 will be entered within the channel in the cross-piece 3^c and bear upward against the cross-piece when the seat rests upon the lugs 24 and 25 with the 60 tenons 22 and 23 in the mortises of the bosses

19 and 20. In this way the seat serves to lock the rear leg section 3 in place and to give it further rigidity.

Attention is called to the fact that every section is flat and that the sections are susceptible of being compactly arranged, as illustrated in Fig. 4, and shipped in a flat box of relatively small dimensions. The chair is readily assembled and disassembled. In assembling the sections, one of the side-sections, for example, section 1, may be held approximately in its normal upright position and the back-section 4 be applied to the side back-piece 1^c with the tenon 11 in the mortise 6 and the tenon 13 in the mortise 8. 75 The other side-section 2 will then be applied to the back-section 4 by entering the tenon 12 in the mortise 7 and the tenon 14 in the mortise 9. The back leg-section 3 will then be assembled by entering the tenons 17 and 18 in the mortises 15 and 16. At this stage 80 of the assembly the structure is normally self-supporting and need no longer be held in position by the one doing the assembling, but may be stood upon its four legs. The 85 seat section 5 will finally be applied. This is done by first entering the ledge 21 within the channel of the cross-piece 3^c. The tenons 22 and 23 are then entered in their respective mortises in the bosses 19 and 20 and the 90 front edge of the seat is then pushed down until the spring washers 22^a and 23^a pass through the mortises. In this position the seat rests upon the lugs 24 and 25 and bears upward with its rear end against the inner face of the channel in the cross-piece 3^c. This lever action of the seat-section 5 holds the back leg-section 3 firmly against the under edges of the respective side seat-pieces 1^a and 2^a and prevents spreading or movement at this point. The engagement of the tenons 13 and 14 in the mortises 8 and 9 prevents any upward movement of the back 95 rest section 4. The tenons 11 and 12 are thus also held firmly in the mortises 6 and 7 and serve as a tie to hold the upper ends of the side-sections against separating. The various members thus assembled are firmly locked and intersupported, the seat-section serving as the key-section which is releasably locked 100 in place by the spring washers 22^a and 23^a. The seat-section 5 is shown as a hollow frame for holding a suitable filler 5^a. The form of spring lock shown may, of course, be modified or may be dispensed with altogether. The characteristic of this particular construction is the fact that this seat when 105 in place rigidly locks all the other sections into a firm, unitary chair. Obviously, the seat may be secured in place in other ways 110 than in the manner shown. For example, it may be held by bolts or screws, although the particular form of interlocking construction shown has advantages which will be 115 readily recognized. The chair may, of 120

course, be sectioned in other ways than that illustrated and still have each section flat, although I have found this particular arrangement to make a very rigid structure when assembled.

It is obvious that various other modifications may be made in the construction shown in the drawings and above particularly described within the principle and scope of my invention.

I claim:

1. A chair or the like composed of a plurality of flat separable sections, two of the sections being side pieces for the seat and a leg integral with each piece, another section being the other two legs joined at the top by a cross piece, and another section being a seat; means for securing the ends of the cross piece to the free ends of the side pieces, means for securing the seat to the side pieces at the corners where they join the integral legs, and means carried by the seat at its other end to lock the cross-piece against detachment from the side pieces.

2. A chair or the like comprising a plurality of flat separable sections, two of the sections being side pieces for the seat with the corresponding front leg integral with each piece, another section being the two back legs joined at the top by a cross piece, and another section being a seat; means for securing the ends of the cross piece to the rear ends of the side pieces, and means for securing the seat to the side pieces at the front corners and for interlocking the rear edge of the seat and the cross piece.

3. A chair or the like comprising a plurality of flat separable sections, two of the sections being respectively left and right hand side pieces including a side seat-piece and a front leg integral with one end and a side back-piece integral with the other end, another section being a back rest section attached to the side back-pieces, another section being the two back legs joined at their top by a cross piece and attached to the rear ends of the side seat-pieces, and another section being a seat attached to the side seat-pieces.

4. A knock-down chair comprising a plurality of flat interlocking sections, two of the sections being respectively legs and right hand side pieces including a side seat-piece and a front leg integral with one end and a side back-piece integral with the other end, another section being a back filling section, means for interlocking said back leg-piece with the side back-pieces, another section being the two back legs joined at their top by a

cross piece and interlocking with the rear ends of the side seat-pieces, and another section being a seat having means for interlocking with the said cross piece and side seat-piece and locking the sections together.

5. A metal chair comprising a pair of side piece members and tie members therebetween, comprising a back member, mortise and tenon elements interlocking said back member with said side members, and a back leg piece comprising a pair of leg members and an integral cross member uniting their upper ends, and mortise and tenon elements for directly uniting said side piece members and said back leg piece.

6. A metal chair comprising a pair of side piece members and tie members therebetween, comprising a back member, mortise and tenon elements interlocking said back member with said side members, a back leg piece comprising a pair of leg members, an integral cross member uniting their upper ends, mortise and tenon elements for directly uniting said side piece members and said back leg piece, and means comprising a seat member and angle projections on said side pieces and a ledge on said back leg piece for interlocking said back leg piece with said side members.

7. A metal chair comprising a pair of side piece members and tie members therebetween, comprising a back member, mortise and tenon elements interlocking said back member with said side members, a back leg piece comprising a pair of leg members, an integral cross member uniting their upper ends, mortise and tenon elements for directly uniting said side piece members and said back leg piece, means comprising a seat member and angle projections on said side pieces and a ledge on said back leg piece for interlocking said back leg piece with said side members, in interlocked engagement.

8. A chair comprising a pair of side piece members provided with inwardly extending front and rear seat supports, a back leg piece comprising a pair of leg members, an integral channeled cross member uniting their upper ends, means for interlocking said cross member with said side members, a seat member supported on said rear seat supports having a projection along the rear edge thereof and detachably secured to said front supports, said projection on said seat member adapted to engage a web of said channel in said cross member.

In witness whereof, I hereunto subscribe my signature.

ANTOINE VERICEL.
